RAILWAY SIGNAL SYSTEM

Howard A. Thompson, Edgewood, Pa., assignor to
The Union Switch & Signal Company, Swiss-
vale, Pa., a corporation of Pennsylvania

Application April 17, 1940, Serial No. 330,122

12 Claims. (Cl. 246—38)

My invention relates to a railway signaling system, and particularly to improved means for extending the control of the signals to provide increased braking distance without increasing the distance between adjacent signals.

It is an object of this invention to provide an improved signaling system employing the standard coded signaling apparatus together with means to employ steady or uncoded energy for detecting the presence of a train in an overlap section.

A further object of the invention is to provide an improved signaling system arranged to insure that there is always an unoccupied space of at least a minimum distance in advance of the point at which the stop or most restrictive indication is given to a following train.

Another object of the invention is to provide an improved signaling system which operates to provide two different proceed indications, and which makes it possible to obtain substantially the same close spacing of trains as is obtained where signaling systems capable of displaying a larger number of different proceed indications are employed.

A further object of the invention is to provide an improved signaling system having block sections divided into two track sections, and arranged so that there is always at least one such track section which is vacant in advance of the point at which a stop or the most restrictive indication is given to a following train.

Other objects of the invention and features of novelty will be apparent from the following description taken in connection with the accompanying drawing.

I shall describe one form of improved signaling system embodying my invention and shall then point out the novel features thereof in claims.

In the drawing, Fig. 1 is a diagram of a stretch of railroad track equipped with signaling apparatus embodying my invention, and

Figs. 2 and 3 are diagrams showing the types of energy supplied to successive track circuits under different conditions of track occupancy.

Referring to Fig. 1 of the drawing, there is shown therein a stretch of railway track having track rails 1 and 2 over which traffic normally moves in the direction indicated by the arrow, that is, from left to right.

The rails of the track stretch are divided by insulated joints 3 into block sections, while the rails of each of the block sections are divided by insulated joints 3 into forward and rearward track sections. Two complete block sections are

shown. These have four track sections which are designated A11T, B11T, A12T and B12T, while portions of two other block sections are shown and are designated B10T and A13T.

Each block section has at the entrance end thereof a wayside signal designated S together with a prefix corresponding to that of the block section with which the signal is associated. As shown the signals are of the familiar color light type each having a green or clear lamp G, a yellow or caution lamp Y, and a red or stop lamp R.

It is to be understood that the invention is not limited to a system employing wayside signals of this type, but that any appropriate type of signals may be employed. Similarly the invention is not limited to use on track stretches employing wayside signals, and is peculiarly applicable to track stretches in which cab signals only are employed.

The track rails of each of the track sections form a part of a track circuit to which alternating current is supplied at the exit end of the section from the secondary windings of a track transformer TT. The circuits of the transformer secondary windings include the usual current limiting reactors 6.

The alternating current employed in the track circuits may be supplied from any suitable source, and may be distributed throughout the track stretch by a transmission line, not shown. The terminals of the source of alternating current are designated BX and CX in the drawing, while it will be assumed that the alternating current has a frequency of 100 cycles per second.

Each of the track sections has at the entrance end thereof a code following track relay TR having a winding receiving energy from the rails of the section through a resonant rectifier unit RU.

The resonant rectifier units RU each comprise a transformer, a reactor and a capacitor arranged and proportioned so as to freely pass 100 cycle alternating current energy, and so as not to pass energy of a different frequency. Each of the resonant units includes, in addition, a rectifier which converts into direct current the alternating current energy which is supplied through the unit.

The track section at the rearward or entrance end of each block section has an auxiliary or second track relay TRA having a winding which is connected in series with the winding of the code following or first track relay TR.

The code following track relay TR for the section at the entrance end of each block section has

associated therewith decoding means comprising a decoding transformer DT and auxiliary relays H and J.

The decoding means is not a part of this invention and any suitable apparatus may be employed for this purpose. The decoding means illustrated is shown and claimed in application Serial No. 210,744, of Frank H. Nicholson and Leslie R. Allison, filed May 28, 1938, for Railway traffic controlling apparatus.

As hereinafter explained the relays H and J cooperate to control the circuits of the lamps of the associated wayside signal, while the relay H and the track relay TRA cooperate to control the supply of energy to the rails of the adjacent section in the rear. In addition, the relay H controls a circuit for at times short circuiting the winding of the auxiliary track relay TRA.

The signaling system shown in the drawing makes use of track circuit energy coded at two different frequencies. This coded energy is provided by code transmitters CT having two circuit making and breaking contacts 75 and 180 which are continuously actuated by a motor or other suitable apparatus. The rate of operation of these contacts is such as to provide 75 and 180 energy impulses per minute which are separated by periods of equal duration during which no energy is supplied.

The track relay TR of the track section at the entrance end of each block section has associated therewith a source of direct current, such as a primary or storage battery, not shown, the terminals of which are designated B and C in the drawing.

The equipment is shown in Fig. 1 in the condition which it assumes when the track stretch is vacant. At this time the equipment, not shown, associated with section A13T operates, as hereinafter explained in connection with the equipment associated with section A12T, to supply energy of the 180 code frequency through the track transformer B12TT to the rails of section B12T with the result that the relay B12TR responds to coded energy.

During the released periods of the contact 20 of track relay B12TR the circuit for supplying energy to the primary winding of track transformer A12TT is established, while this circuit is interrupted during the picked-up periods of the track relay contact so that the energy supplied to the transformer A12TT is coded or interrupted at the same frequency as the energy which is supplied to the track relay B12TR.

Energy supplied to the rails of section A12T feeds through the resonant rectifier unit A12RU to the winding of relay A12TR and produces code following operation of the relay contacts. Accordingly contact 21 of relay A12TR alternately establishes the circuits for energizing the upper and lower portions of the primary winding 22 of the decoding transformer A12DT, while as a result of this energization of the two portions of the primary winding 22 current is induced in the secondary windings 23 and 24. The contact 25 rectifies the current supplied from the winding 24 to the winding of the relay A12H with the result that the contacts of the relay A12H are picked up.

As the track relay A12TR is responding to energy of the 180 code frequency, the frequency of the energy induced in the winding 23 is such that it is freely passed by the resonant rectifier unit A12RUA and sufficient energy is supplied

to the winding of relay A12J to pick up the contact of this relay.

As contact 27 of relay A12H is picked up, a circuit is established shunting the winding of the second track relay A12TRA with the result that the winding of this relay is not energized at this time and its contact 28 remains released.

As the contact 29 of relay A12H and the contact 30 of relay A12J are picked up, the circuit of the green or clear lamp G of signal 12S is established, while as contact 32 of relay A12H is picked up, the circuit for supplying energy of the 180 code frequency to the track transformer B11TT is established.

On the supply of energy of 180 code frequency to the track relay B11TR this relay operates in the same manner as relay B12TR to repeat the supply of energy of this code frequency to the rails of section A11T. On the supply of energy of the 180 code frequency to the track relay A11TR the equipment associated with this relay operates in the manner explained in detail in connection with section A12T to condition the signal 11S to display its green or clear indication, while energy of the 180 code frequency is supplied to the rails of section B10T.

Operation of equipment on passage of a train through the track stretch

When a train moving in the normal direction of traffic enters section A11T, the track relay A11TR is shunted and ceases to follow code with the result that energy is no longer supplied through the decoding transformer A11DT to the windings of relays A11H and A11J and the contacts of these relays become released.

As a result of release of contact 29 of relay A11H, the circuit of the green or clear lamp G of signal 11S is interrupted, while the circuit of the red or stop lamp R is established. On release of the contact 32 of relay A11H the circuit for supplying energy of the 180 code frequency to the rails of section B10T is interrupted, while as contact 28 of the second track relay A11TRA is released, the circuit for supplying energy of the 75 code frequency to the rails of section B10T is also interrupted with the result that no energy is supplied to the rails of section B10T.

On release of contact 27 of the relay A11H the circuit shunting the winding of the second track relay A11TRA is interrupted, but as the rails of section A11T are shunted at this time, energy is not supplied to the winding of relay A11TRA and the contacts of this relay remain released.

When the train advances far enough in the track stretch to enter section B11T, the relay B11TR is shunted, and its contact 20 remains in its released position so that steady uncoded energy is supplied to the rails of section A11T.

As long as any portion of the train remains in section A11T, the track relays A11TR and A11TRA are shunted with the result that no energy is supplied to the rails of section B10T. When the rear of the train vacates section A11T, steady energy supplied over contact 20 of track relay B11TR feeds through the resonant rectifier unit A11RU to the windings of the track relays A11TR and A11TRA in series, and the contacts of these relays become picked up.

On picking up of contacts 21 and 25 of relay A11TR an impulse of energy is supplied through the decoding transformer A11DT to the winding of the relay A11H, but this relay and the decoding transformer are proportioned so that relay contacts will not become picked up on the

supply of one impulse of energy to the relay winding. Accordingly, the relay contacts remain released, and contact 27 continues to interrupt the circuit shunting the winding of the second track relay A11TRA so that the winding of relay A11TRA is energized by current supplied through the resonant rectifier unit A11RU.

As a result of picking up of contact 28 of relay A11TRA, the circuit for supplying energy of the 75 code frequency to the rails of section B10T is established, and the signal next in the rear of signal 11S is conditioned to display its approach or caution indication instead of its stop indication.

When the train advances into section A12T, the track relay A12TR is shunted and the contacts of relays A12H and A12J become released, while the contacts of the second track relay A12TRA remain released, as explained in detail in connection with section A11T. The signal 12S accordingly is conditioned to display its stop indication, while the supply of energy to the rails of section B11T is cut off.

As no energy is supplied to the rails of section B11T, the contact 20 of track relay B11TR remains released after the train vacates section B11T, and the supply of steady energy to the rails of section A11T is maintained so that the signal 11S continues to display its stop indication, while energy of the 75 code frequency continues to be supplied to the rails of the adjacent section in the rear.

When the train advances into section B12T, the track relay B12TR is shunted and its contact 20 establishes the circuit to supply steady energy to the rails of section A12T. When the train vacates section A12T, the steady energy feeds to the track relays A12TR and A12TRA, and on picking up of the contact 28 of relay A12TRA the circuit for supplying energy of the 75 code frequency to the rails of section B11T is established. This energy produces code following operation of the track relay B11TR with the result that the energy supplied to the rails of section A11T is changed from steady energy to energy of 75 code frequency.

On the supply of coded energy to the rails of section A11T this energy feeds through the resonant rectifier unit A11RU and produces code following operation of the track relays A11TR and A11TRA.

Since steady energy is supplied to the track relays A11TR and A11TRA prior to the time that coded energy is supplied to these relays, the contacts of the relays are in their picked-up positions at the time the supply of coded energy to these relays is initiated. Accordingly, on the supply of coded energy to these relays their contacts remain picked up until the first "off" period in the code, whereupon the contacts of the relays become released. On the first movement of the contacts of the relay A11TR to their released positions an impulse of energy is supplied to the winding of relay A11H from the decoding transformer A11DT, but, as pointed out above, the contacts of the relay A11H will not become picked up on the supply of a single impulse of energy to the relay winding. The contacts of relay A11H, therefore, remain released on the first movement of the contacts of track relay A11TR to their released position. Another impulse of energy is supplied to the winding of relay A11H on the first movement of the track relay contacts to their picked-up posi-

tion, and on the supply of this impulse of energy to the winding of the relay A11H the relay contacts become picked up.

On the first "off" interval in the code supplied to the relays A11TR and A11TRA the contact 28 of the relay A11TRA becomes released and interrupts the circuit for supplying energy of the 75 code frequency to the rails of section B10T.

On the first "on" period following the first "off" period in the code supplied to the relays A11TR and A11TRA contact 28 of relay A11TRA may become picked up again, but at this time contact 32 of relay A11H also becomes picked up and interrupts the circuit for supplying energy of the 75 code frequency to the track transformer B10TT so that picking up of the contact 28 of relay A11TRA is without result.

On picking up of the contact 32 of relay A11H the circuit for supplying energy of the 180 code frequency to the rails of section B10T is established, while as a result of picking up of contact 27 of relay A11H the circuit shunting the winding of the second track relay A11TRA is established, and the contact of this relay becomes released if it has become picked up.

In addition, on picking up of the contacts of relay A11H contact 29 interrupts the circuit of the red or stop lamp R and establishes the circuit of the yellow or caution lamp Y of signal 11S.

From the foregoing it will be seen that when a train enters a block section, the signal for that section is caused to display its red or stop indication, and that when the train vacates the block section, the signal continues to display its red or stop indication until the train vacates the rearward track section of the adjacent block section in advance.

Thus, it will be seen that the signal 11S is conditioned to display its stop indication when a train enters section A11T, and that the signal continues to display its stop indication until the train has advanced far enough in the track stretch to vacate section A12T, that is, the rearward track section of the block section next in advance of that with which the signal 11S is associated.

Similarly, when the train advances far enough in the track stretch to clear section A13T, the equipment associated with section A12T operates as described above to condition the signal 12S to display its yellow or caution indication, while the energy supplied to the rails of section B11T is changed from 75 to 180 code frequency. On this change in the frequency of the code supplied to the rails of section B11T the track relay B11TR repeats the supply of energy of the higher code frequency to the rails of section A11T. On the supply of energy of the 180 code frequency to the relay A11TR its contacts operate at the higher speed and sufficient energy is supplied through the resonant rectifier unit A11RUA to pick up the contact of the relay A11J, while on picking up of the contact 30 the signal 11S is conditioned to display its green or clear indication instead of its yellow or caution indication.

Figs. 2 and 3 of the drawing are diagrams showing the condition of the signals and the types of energy supplied to the track circuits of a track stretch under different conditions of track occupancy.

When the track stretch is vacant, coded energy, which may be considered to be energy of a first character, is supplied to the track circuits of the

various track portions in the track stretch, and the signals for the various block sections are conditioned to display their green or clear indications, while energy of this character is operative to condition the cab signal apparatus on a locomotive traversing the track stretch to display a proceed indication.

As is shown in Fig. 2, when a train is present in the forward track section of a block section, steady energy, which may be considered to be energy of a second character, is supplied to the rails of the rearward track section of the same block section with the result that the signal for that block section is conditioned to display its stop or most restrictive indication, while energy of the first character, that is, coded energy, but of the 75 code frequency, is supplied to the track sections of the adjacent block section in the rear with the result that the signal for that block section display its yellow or caution indication.

Under the condition of track occupancy illustrated in Fig. 2 a second or following train will receive a restrictive indication at the entrance to the block section next in the rear of that in which the first train is located. At this time there are three unoccupied track sections in the rear of the first train, these three track sections being the two sections of the block governed by the signal 12S, and the rearward one of the sections of the block governed by the signal 13S. Under these conditions, therefore, the second or following train has a distance equal to at least one and a half block sections in which to stop after passing a signal displaying a restrictive indication.

Fig. 3 is a diagram showing the condition of the apparatus when a train is present in the rearward track section of a block section. Under this condition the signal at the entrance to the occupied block displays its stop indication and no energy is supplied to the forward track section of the adjacent block section in the rear, while steady energy is supplied to the rails of the rearward track section of that block section with the result that the signal for the block section next in the rear of the occupied block section also displays its stop indication. Energy of the 75 code frequency is supplied to the rails of the track sections of the second block section in the rear of the occupied block section, and the signal for that section is conditioned to display its caution indication, while energy of the 180 code frequency is supplied to the sections in the rear.

It will be seen that under the condition of track occupancy illustrated in Fig. 3, a second or following train will receive a restrictive proceed indication at the entrance to the second block section in the rear of the occupied block, and that at this time there are two full block sections or four track sections in the rear of the first train which are unoccupied.

Since with the signaling system provided by this invention the braking distance in advance of the signal displaying a restrictive indication is always equal to at least one and a half blocks, the blocks can be somewhat shorter than would otherwise be necessary to provide adequate braking distance with the result that relatively close spacing of trains running under clear conditions is obtained.

In addition, it will be seen that there is always at least one unoccupied track section in advance of a signal displaying a stop or the most restrictive indication. As shown in Fig. 2, when a train is in the forward track section of a block section,

there is one vacant track section in advance of the first signal displaying a stop indication, while as shown in Fig. 3, when the train is in the rearward track section of a block section, there are

5 two signals in the rear of the train which display stop indications, and there are two unoccupied track sections in advance of the first signal displaying a stop indication. This unoccupied space in advance of a signal displaying a stop indication provides a factor of safety and prevents collisions if for any reason a second or following train should run past the stop signal.

The unoccupied track section in advance of the point at which a stop indication is given to a 15 second or following train is particularly valuable in signaling systems employing cab signals only.

In the usual system having cab signals only the stop indication is not received on the locomotive of a second or following train until the 20 locomotive is present in an occupied section. In such a system if the first train stops with the rear end thereof adjacent the entrance end of a section, a second or following train may not have distance enough in which to stop after receiving 25 the stop indication.

The cab signal apparatus which is adapted to be employed on locomotives operating in track stretches equipped with signaling apparatus embodying this invention is arranged to respond to 30 coded alternating current energy, that is, to energy of the first character to provide proceed indications, while the apparatus responds to steady uncoded alternating current, that is, to energy of the second character, or to the absence 35 of energy to provide a stop indication.

In the system provided by this invention there is always at least one track section in the rear of a train to which steady uncoded energy is supplied with the result that the cab signal apparatus on a second or following train will be 40 conditioned to provide the stop indication at a point at least one track section behind the first train. This gives the engineer of the second or following train notice that he is approaching an 45 occupied section before the locomotive actually enters the track section in which the first train is located.

It will be seen that the system provided by this 50 invention employs energy of a first character, that is, energy of the normal code frequencies, in the track circuits to control the signals, while it employs energy of a different or second character, that is, steady energy, in the track circuit of an overlap portion to extend the control of the signals. While the use of steady energy in the overlap 55 portion has been shown, any distinctive form of energy may be employed for this purpose.

Similarly, although the invention has been described in connection with a signaling system employing coded and steady alternating current in the track circuits thereof to provide the two characters of energy required in the system, the invention is not limited to the use of this combination of characters of energy. Instead direct 60 current, either steady or coded, may be employed in the track circuits of the various track portions, while the two polarities of direct current may be employed to provide different proceed indications or to distinguish between train detecting energy 65 in an overlap portion and signal control energy. Likewise, it is contemplated that the necessary two characters of energy may be obtained by employing a combination of alternating and direct current, or by employing energy coded at distinctive frequencies.

Although I have herein illustrated and described only one form of railway signaling system embodying my invention, it is understood that various changes and modifications may be made therein within the scope of the appended claims without departing from the spirit and scope of my invention.

Having thus described my invention, what I claim is:

1. In a railway signaling system, in combination, a stretch of railway track having a pair of track rails over which traffic moves in a given direction, the rails having insulated joints therein to divide the track stretch into a plurality of successive block sections, the rails of each of the block sections being divided by insulated joints into a forward and a rearward portion, the forward portion of each block section having an electroresponsive device having a winding receiving energy over the rails of said portion, each such device being operative when and only when supplied with energy of a first character to effect the supply of energy of said first character to the rails of the rearward portion of the same block section and operative when not energized to effect the supply of energy of a second character to the rails of said rearward portion, the rearward portion of each of said block sections having electroresponsive means receiving energy from the rails of said portion, said means being operative when and only when supplied with energy of either the first or the second character to effect the supply of energy of the first character to the rails of the forward portion of the adjoining block section in the rear and being operative when not energized to continuously cut off the supply of energy to the rails of said forward portion of the adjoining block section in the rear, and traffic governing means for each of said block sections selectively controlled by the electroresponsive means associated with the rearward portion of said block section in accordance with the character of the energy supplied to the said means.

2. In a railway signaling system, in combination, a stretch of railway track having a pair of track rails over which traffic moves in a given direction, the rails having insulated joints therein to divide the track stretch into a plurality of successive block sections, the rails of each of the block sections having insulated joints therein to divide the section into a forward and a rearward portion, the rearward portion of each block section having electroresponsive means having a winding receiving energy over the rails of said portion, each such means being operative when and only when supplied with energy of either a first or a second character to supply energy of the first character to the rails of the forward portion of the adjacent block section in the rear, said means being operative when not energized to continuously cut off the supply of energy to the rails of such forward portion, the forward portion of each block section having electroresponsive means having a winding receiving energy over the rails of said forward portion, each such means associated with a forward portion being operative when and only when supplied with energy of the first character to effect the supply of energy of the first character to the rails of the rearward portion of the same block section and being operative when not energized to effect the supply of energy of the second character to the rails of the rearward portion of the same block section, whereby energy of the

first character is supplied to the rails of the rearward portion of each block section when and only when the forward portion of said block section and the rearward portion of the adjacent block section in advance are both unoccupied, and whereby at all other times energy of the second character is supplied to the rails of such rearward portion, and traffic governing means for each of said block sections selectively controlled by the electroresponsive means associated with the rearward portion of said block section in accordance with the character of the energy supplied to said means.

3. In a railway signaling system, in combination, a stretch of railway track having a pair of track rails over which traffic moves in a given direction, the rails of said stretch having insulated joints therein to divide the track stretch into a plurality of successive block sections, the rails of each of said block sections having insulated joints therein to divide the section into a forward and a rearward portion, the rearward portion of each of said block sections having electroresponsive means having a winding receiving energy over the rails of said portion, said means being operative when deenergized to continuously cut off the supply of energy to the rails of the forward portion of the adjoining section in the rear, said means being operative when energized with energy of a first type to effect the supply of energy of a second type to the rails of the forward portion of the adjoining section in the rear and being operative when energized with energy of said second type or of a third type to effect the supply of energy of the third type to the rails of the forward portion of the adjoining section in the rear, the forward portion of each block section having electroresponsive means having a winding receiving energy over the rails of said forward portion, each such means being operative when supplied with energy of the second or third types to effect the supply of energy of the same type to the rails of the rearward portion of the same block section and being operative when not energized to effect the supply of energy of the first type to the rails of the rearward portion of the same block section, each of the block sections having at the entrance end thereof a signal governing traffic in said section, the signal for each section being selectively controlled by the electroresponsive means for the rearward portion of the said section in accordance with the type of current supplied to the said means.

4. In a signaling system for a stretch of railway track, in combination, a pair of conductors divided into block sections, the conductors of each block section being divided into a forward portion and a rearward portion, the conductors of each portion being governed by traffic conditions in such portion, the rearward portion of each of said block sections having electroresponsive means having a winding receiving energy over the conductors of the said portion, each such means being operable when supplied with energy of a first or a second character to supply energy of the first character to the conductors of the forward portion of the adjacent block section in the rear and being operative when not energized to continuously cut off the supply of energy to the conductors of such forward portion, the forward portion of each block section having electroresponsive means having a winding receiving energy over the conductors of the said portion, each such means associated with a forward por-

tion being operative when and only when supplied with energy of the first character to effect the supply of energy of the first character to the conductors for the rearward portion of the same block section and being operative when not energized to effect the supply of energy of the second character to the conductors of the rearward portion of the same block section, whereby the conductors of the rearward portion of each block section are supplied with energy of the first character when and only when the forward portion of the same block section and the rearward portion of the adjacent block section in advance are both unoccupied and whereby at all other times energy of the second character is supplied to the conductors of such rearward portion, and traffic governing means for each of said block sections selectively controlled by the electroresponsive means of the rearward portion of such section in accordance with the character of the energy supplied to such means.

5. In a railway signaling system of the type having traffic governing means selectively responsive to different characters of energy, in combination, a stretch of railroad track having a pair of track rails over which traffic moves in a given direction, the rails of the stretch being divided by insulated joints into a plurality of successive block sections, the rails of each of said block sections being divided by insulated joints into a forward and a rearward portion, the rearward portion of each block section having electroresponsive means having a winding receiving energy over the rails of said portion, each such means being operative when and only when supplied with energy of either a first or a second character to supply energy of the first character to the rails of the forward portion of the adjacent block section in the rear, said means being operative when not energized to continuously cut off the supply of energy to the rails of the forward portion of the adjacent section in the rear, the forward portion of each block section having electroresponsive means having a winding receiving energy over the rails of said forward portion, each such means associated with a forward portion being operative when and only when supplied with energy of the first character to effect the supply of energy of the first character to the rails of the rearward portion of the same block section and being operative when not energized to effect the supply of energy of the second character to the rails of the rearward portion of the same block section, whereby energy of the first character is supplied to the rails of the rearward portion of each block section when and only when the forward portion of said block section and the rearward portion of the adjacent block section in advance are both unoccupied and whereby at all other times energy of the second character is supplied to the rails of such rearward portion.

6. In a railway signaling system of the type having traffic governing means selectively responsive to different characters of energy supplied to the rails of a track stretch, in combination, a stretch of railway track having a pair of track rails over which traffic normally moves in a given direction, the rails of said stretch being divided by insulated joints into a plurality of successive block sections, the rails of each of the said sections being divided by insulated joints into a forward and a rearward portion, the rearward portion of each block section having an electroresponsive device having a winding re-

ceiving energy over the rails of said portion, each such means being operative when and only when supplied with coded or uncoded energy to supply coded energy to the rails of the forward portion of the adjoining section in the rear, each such means being operative when not energized to continuously cut off the supply of energy to the rails of such forward portion, the forward portion of each block section having electroresponsive means having a winding receiving energy over the rails of said forward portion, each such means associated with a forward portion being operative when and only when supplied with coded energy to effect the supply of coded energy to the rails of the rearward portion of the same block section and being operative when not supplied with energy to effect the supply of uncoded energy to the rails of the said rearward portion.

7. In a railway signaling system, in combination, a stretch of railway track having a pair of track rails over which traffic moves in a given direction, the rails of the stretch being divided by insulated joints into a plurality of successive block sections, the rails of each of said block sections being divided by insulated joints into a forward and a rearward portion, the rearward portion of each block section each having a first and a second track relay each having a winding receiving energy over the rails of the said portion, each of said second track relays controlling means operative when and only when uncoded energy is supplied to said relay winding to establish a circuit to supply coded energy to the rails of the forward portion of the adjoining block section in the rear, each of said first track relays controlling means operative when and only when coded energy is supplied to the relay winding to render the associated second track relay non-responsive to coded energy and to establish a circuit to also supply coded energy to the rails of the forward portion of the adjoining block section in the rear, the forward portion of each block section having a track relay having a winding receiving energy over the rails of such portion, each such forward portion track relay being operative on the supply of coded energy thereto to effect the supply of coded energy to the rails of the rearward portion of the same block section and being operative when not energized to effect the supply of uncoded energy to the rails of the rearward portion of the same block section, and traffic governing means for each block section selectively controlled by the first track relay of the rearward portion of said block section.

8. In a railway signaling system of the type having traffic governing means selectively responsive to different characters of energy supplied to the rails of a track stretch, in combination, a stretch of railway track having a pair of track rails over which traffic normally moves in a given direction, the rails of said stretch being divided by insulated joints into a plurality of successive block sections, the rails of each of the block sections being divided by insulated joints into a forward and a rearward portion, the rearward portion of each block section each having a first and a second track relay each having a winding receiving energy over the rails of the said portion, each of said second track relays controlling means operative when and only when uncoded energy is supplied to said relay winding to establish a circuit to supply coded energy to the rails of the forward portion

of the adjoining block section in the rear, each of said first track relays controlling means operative when and only when coded energy is supplied to the relay winding to render the associated second track relay non-responsive to coded energy and to establish a circuit to also supply coded energy to the rails of the forward portion of the adjoining block section in the rear, the forward portion of each block section having a track relay having a winding receiving energy over the rails of such section, each such forward portion track relay being operative on the supply of coded energy thereto to effect the supply of coded energy to the rails of the rearward portion of the same block section and being operative when not energized to effect the supply of uncoded energy to the rails of the rearward portion of the same block section.

9. In a railway signaling system, in combination, a stretch of railway track having a pair of track rails over which traffic normally moves in a given direction, the rails of said stretch being divided by insulated joints into a plurality of successive block sections, the rails of each of said block sections being divided by insulated joints into a forward and a rearward portion, the rearward portion of each block section each having a first and a second track relay each having a winding receiving energy over the rails of said rearward portion, each of said second track relays controlling means operative when and only when uncoded energy is supplied to said relay winding to establish a circuit to supply coded energy of a first code frequency to the rails of the forward portion of the adjoining block section in the rear, each of said first track relays controlling means operative when and only when coded energy is supplied to the relay winding to render the associated second track relay non-responsive to coded energy and to establish a circuit to supply coded energy of a second code frequency to the rails of the forward portion of the adjoining block section in the rear, the forward portion of each block section having a track relay having a winding receiving energy over the rails of such portion, each such forward portion track relay being operative on the supply of coded energy of either code frequency thereto to effect the supply of coded energy of the same code frequency to the rails of the rearward portion of the same block section and being operative when not energized to effect the supply of uncoded energy to the rails of the rearward portion of the same block section, and traffic governing means for each block section selectively controlled by the first track relay of the rearward portion of such block section in accordance with the supply of coded energy to said track relay and also in accordance with the code frequency of such energy.

10. In a railway signaling system of the type having traffic governing means selectively responsive to energy of different code frequencies supplied to the rails of a track stretch, in combination, a stretch of railway track having a pair of track rails over which traffic normally moves in a given direction, the rails of said stretch being divided by insulated joints into a plurality of successive block sections, the rails of each of said block sections being divided by insulated joints into a forward and a rearward portion, the rearward portion of each block section each having a first and a second track relay each having a winding receiving energy over the rails of the said portion, each of said second track relays controlling means operative when and only when

uncoded energy is supplied to said relay winding to establish a circuit to supply coded energy of a first code frequency to the rails of the forward portion of the adjoining block section in the rear, each of said first track relays controlling means operative when and only when coded energy is supplied to the relay winding to render the associated second track relay non-responsive to coded energy and to establish a circuit to supply coded energy of a second code frequency to the rails of the forward portion of the adjoining block section in the rear, the forward portion of each block section having a track relay having a winding receiving energy over the rails of such portion, each forward portion track relay being operative on the supply thereto of coded energy of either code frequency to effect the supply of coded energy of the same code frequency to the rails of the rearward portion of the same block section and being operative when not energized to effect the supply of uncoded energy to the rails of the rearward portion of the same block section in the rear.

11. In a railway signaling system of the type having traffic governing means selectively responsive to energy of different code frequencies supplied to the rails of a track stretch, in combination, a stretch of railway track having a pair of track rails over which traffic normally moves in a given direction, the rails of said track stretch being divided by insulated joints into a plurality of successive block sections, the rails of each of said block sections being divided by insulated joints into a forward and a rearward portion, the rearward portion of each block section each having a first and a second track relay each having a winding, the windings of said track relays being connected in series and receiving energy over the rails of such rearward portion, each first track relay having associated therewith an auxiliary relay and means responsive to operation of the track relay contacts to supply energy to the auxiliary relay winding, each second track relay being operative when its winding is energized to establish a circuit to supply coded energy of a first code frequency to the rails of the forward portion of the adjoining block section in the rear, each auxiliary relay being operative when its winding is energized to establish a circuit shunting the winding of the associated second track relay and to also establish a circuit to supply coded energy of a second code frequency to the rails of the forward portion of the adjoining block section in the rear the forward portion of each block section having a track relay having a winding receiving energy over the rails of such portion, each forward portion track relay being operative on the supply thereto of coded energy to effect the supply of coded energy of the same code frequency to the rails of the rearward portion of the same block section and being operative when not energized to effect the supply of uncoded energy to the rails of the rearward portion of the same block section.

12. In a railway signaling system of the type having traffic governing means selectively responsive to energy of different code frequencies supplied to the rails of a track stretch, in combination, a stretch of railway track having a pair of track rails over which traffic normally moves in a given direction, the rails of said stretch being divided by insulated joints into a plurality of successive block sections, the rails of each of said block sections being divided by insulated

joints into a forward and a rearward portion, the rearward portion of each block section having a first and a second track relay each having a winding receiving energy over said rearward portion, each first track relay having an auxiliary relay associated therewith and having means operative on code following operation of the track relay to supply energy to the associated auxiliary relay, each second track relay being operative when uncoded energy is supplied thereto to establish a first supply circuit to supply coded energy of a first code frequency to the rails of the forward portion of the adjoining block section in the rear, each auxiliary relay being operative when energized to interrupt the

associated first supply circuit and to establish a circuit to supply coded energy of a second code frequency to the rails of the forward portion of the adjoining block section in the rear, the forward portion of each block section having a track relay having a winding receiving energy over the rails of such portion, each forward portion track relay being operative on the supply thereto of coded energy to effect the supply of coded energy of the same code frequency to the rails of the rearward portion of the same block section and being operative when not energized to effect the supply of uncoded energy to the rails of the rearward portion of the same block section.

HOWARD A. THOMPSON.
